UNITED STATES PATENT OFFICE.

VERNIE R. HELIN, OF CHICAGO, ILLINOIS.

DESIGN FOR A COMBINATION-TOOL.

58,482.

Specification for Design.

Patented July 26, 1921.

Application filed March 11, 1921. Serial No. 451,591. Term of patent 7 years.

To all whom it may concern:

Be it known that I, VERNIE R. HELIN, a citizen of the United States, residing at Chicago, in the county of Cook and State of Illinois, have invented a new, original, and ornamental Design for a Combination-Tool, of which the following is a specification, reference being had to the accompanying drawing, in which—

Figure 1 is a perspective view of the de-

sign showing one side thereof; Fig. 2 is a similar view showing the opposite side, and Fig. 3 is an elevation showing certain portions of the device unfolded.

I claim:—

The ornamental design for a combination tool, as shown.

In testimony whereof I affix my signature.

VERNIE R. HELIN.
